UNITED STATES PATENT OFFICE.

ARTHUR F. BELL, OF BELLE PLAINE, IOWA, ASSIGNOR OF ONE-HALF TO
LEWIS T. SWEET, OF SAME PLACE.

DESIGN FOR A FENDER.

SPECIFICATION forming part of Design No. 25,806, dated July 21, 1896.

Application filed June 1, 1896. Serial No. 593,931. Term of patent 14 years.

To all whom it may concern:

Be it known that I, ARTHUR F. BELL, a citizen of the United States, and a resident of Belle Plaine, in the county of Benton and State of Iowa, have invented and produced a new and original Design for Fenders or Spark-Arresters; and I do hereby declare that the following is a full, clear, and exact description of the invention, which will enable others skilled in the art to which it appertains to make and use the same, reference being had to the accompanying drawings, which form a part of this specification.

My invention relates to an improved design for fenders for heating and cooking stoves and fireplaces, and which are used for preventing sparks of fire, dirt, and coals of fire from escaping from the stoves or fireplaces to the floor, and thus damaging and injuring carpets and other articles, and sometimes causing serious conflagrations.

The essential feature of the design consists in a fender having its lower portion made plain and the ends curved inwardly and its upper portion curved inwardly and then upwardly and the edge formed with a number of ornamental projections.

In the accompanying drawings, Figure 1 is

a perspective view of a fender constructed in accordance with my design. Fig. 2 is a front elevation of the same.

In the said drawings, the reference-numeral 1 designates the lower portion of the fender, having the ends bent inwardly and formed with a groove 2, extending from end to end. Above this groove the fender and spark-arrester is curved inwardly, forming a rounded portion 3, the upper end of which extends or is bent upwardly, forming a flange 4. At the upper edge this flange is formed with a number of ornamental projections 6, each consisting of a quadrilateral piece with the sides concaved or rounded and connected with the edge of the flange by short strips 7, which are alternately bent inward and outward, thus presenting a neat and attractive appearance.

What I claim is—

The design for a fender and spark-arrester, substantially as shown and described.

In testimony that I claim the foregoing as my own I have hereunto affixed my signature in presence of two witnesses.

ARTHUR F. BELL.
